UNITED STATES PATENT OFFICE.

GEORGE W. BLAIR, OF PITTSBURG, PENNSYLVANIA.

DESIGN FOR A LAMP-CHIMNEY.

SPECIFICATION forming part of Design No. 26,147, dated October 6, 1896.

Application filed May 7, 1896. Serial No. 590,623. Term of patent 14 years.

To all whom it may concern:

Be it known that I, GEORGE W. BLAIR, of Pittsburgh, in the county of Allegheny and State of Pennsylvania, have invented a new 5 and original Design for Lamp-Chimneys, of which the following is a full, clear, and exact description.

As shown in the drawing, the lamp-chimney has opposite to the position of the flame or 10 burner, when the chimney is applied to a lamp, a pattern 3, consisting of closely-adjacent figures in intaglio or relief, giving the chimney

a beaded appearance. Above the pattern 3 the chimney 2 is plain or may be ornamented.

I claim—

The design for lamp-chimney substantially as herein described and shown.

In testimony whereof I have hereunto set my hand.

GEORGE W. BLAIR.
